AUTOMATIC SIGNAL BIAS CONTROL
MEANS AND APPARATUSRobert M. Sprague, Manhasset, N. Y., assignor to
Press Wireless, Inc., Chicago, Ill., a corpora-
tion of Delaware

Application May 23, 1944, Serial No. 536,871

8 Claims. (Cl. 178—6)

1

This invention relates to electric signalling systems employing control oscillators, and wherein the accuracy of signal reproduction is independent of oscillator drift and the like.

A principal object of the invention is to provide a signalling system wherein a control oscillator is used either at the transmitter or at the receiver, and wherein the recording or signal reproduction at a receiving point is controlled by a potential which is arranged to vary symmetrically around a mean or steady value, which mean value is substantially independent of frequency drift in the oscillator.

Another principal object is to provide a method of keying a signal potential symmetrically around a mean value, whereby said mean value is independent of frequency drift in the transmission channel.

Another object is to provide an automatic bias-compensation arrangement for signalling systems of the keyed-signal type.

A feature of the invention relates to a system for transmitting signals such as telegraph or facsimile signals, by means of a variable frequency carrier, and wherein the signal reproduction is substantially unaffected by uncontrolled or accidental frequency drift of the carrier.

A further feature relates to an improved system for transmitting telegraph or facsimile signals by means of a variable frequency carrier, wherein the frequency drift of the mean or base carrier frequency is automatically compensated for, insofar as the reproduced signals are concerned.

Another feature relates to a system of telephoto transmission wherein, at regular intervals during the scanning of the subject matter, a series of impulses are transmitted representing alternately the extreme shades e. g., "black" and "white"; and at the receiver a special symmetrically balanced condenser-rectifier network is employed which is maintained in electrostatic balance under control of said impulses whereby frequency drift in the system ahead of the network does not interfere with the shade recordings.

A further feature relates to an automatic signal bias-control network for use in a telegraph keying system, whereby the signal-controlled excursions of a recording or signal potential are at all times symmetrical with respect to a zero or base potential.

A further feature relates to a system of telegraphy employing a carrier of signal-controlled frequency excursions on either side of a base frequency, and wherein the reproducing device at

2

the receiver is provided with a special signal responsive network for avoiding zero wander.

A still further feature relates to the novel organization, arrangement and relative interconnection of parts which cooperate to produce an improved variable frequency carrier signalling system.

While the invention will be disclosed in connection with a telephoto or telegraph system, this is done merely for explanatory purposes. The application of the inventive concept to other kinds of signalling will be clear after a consideration of the following detailed descriptions and the appended claims. Accordingly, in the drawing,

15 Fig. 1A is a wave diagram representing an original intelligence message to be transmitted.

Fig. 1B shows how the wave form of Fig. 1A is changed at a certain point in the transmission or receiving systems.

20 Fig. 1C shows how the wave of Fig. 1B is reconverted to substantially the original wave shape of Fig. 1A.

Fig. 1D illustrates how the conversion of the wave of Fig. 1B is distorted under certain conditions.

Fig. 2 is a schematic and block diagram of a typical signalling system embodying features of the invention.

In the transmission of such subject matter as 30 photographs and the like over a radio or high frequency channel, it has been proposed to employ a carrier whose frequency is shifted or varied in accordance with the shade values of successively scanned elemental areas of the subject

35 matter. By this method the base or optimum ratio of signal-to-noise is obtained. If during the transmission the base or normal frequency of the transmitter or carrier varies or drifts, there results a change in the average density of the

40 shades in the reproduced subject matter. This undesirable effect is also produced by a drift of the local oscillator when such an oscillator is employed in the radio receiver for detection or demodulation purposes. For a detailed description 45 of one form of carrier shift method of transmission that may be employed herein, reference can be had to U. S. Patent No. 2,387,098, dated Oct. 16, 1945, the disclosure of which is expressly incorporated herein by reference.

50 Where the original subject matter is merely "black" and "white" e. g., printed or written matter, during the transmission period the carrier is subjected to a statistical excursion in frequency between two extremes with respect to its normal or base frequency. This also is true where

the signals being transmitted are the usual telegraph signals of the "mark" and "space" kind. In such systems, it is usual to employ at the receiver, some kind of filter on which these square waves are impressed, with the object of filtering out any extraneous noise frequencies beyond the useful pass-band representing the actual signals. Such filtering action however, very frequently destroys or suppresses the harmonic content of the original square-topped signal waves and leaves only the fundamental thereof. It is necessary therefore, in such systems, to follow the filter with some kind of a peak limiter or the like, whereby the smoothly rounded fundamental frequency waves can be reconstituted into equivalent square-topped waves. I have found that if the transmitting oscillator or the local beat frequency oscillator at the receiver is subject to fortuitous frequency drift, there results a change in the normal bias of the reproduced signal due to the fact that the positive half waves of the reconstituted square-topped waves are not of equal duration with the negative half waves. If the recorder or keying device to be controlled by these reconstituted waves is arranged to record shade variations equally on both sides of a mean shade value e. g., gray, this lack of symmetry in the reconstituted square waves is revealed as a change in the average density of the reproduction.

Fig. 1A shows the original wave shape of telefacsimile or telegraph signals which, for purposes of explanation, are assumed to represent a series of dots in the original subject matter. After these signals are passed through a low-pass filter at the receiver, they assume the shape shown in Fig. 1B. The signals of Fig. 1B are then applied in the usual way to a peak limiter or the like whereby they are reconstituted into square-topped waves as shown in Fig. 1C. If in the meanwhile, the transmitter frequency has drifted, or if the frequency of the local beat oscillator in the receiving radio set has drifted, the base line B of Fig. 1B, will no longer be symmetrical with respect to the positive and negative excursions but will have a non-symmetrical appearance as represented for example in Fig. 1D. I have found that by employing a special form of capacity and rectifier network ahead of the limiter, the undesirable effects of frequency drift are automatically compensated for.

Referring to Fig. 2, there is shown in schematic form a telefacsimile system employing the invention, but with well-known parts of the system omitted for the sake of clarity. The picture or other subject matter 1, to be transmitted, is wrapped around the usual scanning drum 2, which is rotated so that the picture is completely scanned in successive elemental areas in the well-known manner by means of an elemental light spot from source 3. The reflected light excites the photocell 4, whose output is amplified in any suitable amplifying system 5. The amplified signals are then applied through a suitable switch 6 to a radio transmitter preferably of the carrier-shift type comprising a carrier source 7 arranged to generate a normal carrier frequency which will be referred to as the base frequency, and a frequency shifting arrangement 8, whereby the picture signals cause the frequency of the carrier to be shifted between predetermined limits. For a detailed description of a preferred form of carrier shift arrangement that may be used, reference may be had to U. S. application Serial No. 498,278, filed August 12, 1943, the disclosure

of which is expressly incorporated herein by reference. This method of carrier shift is to be distinguished from ordinary amplitude modulation of a carrier, wherein the carrier fundamental frequency remains and has simultaneously upper and lower side bands. The output from device 8 consists at any given instant of a substantially single frequency carrier which however can be varied in frequency. For example, if the subject matter is printed matter or other simple black and white matter, the carrier may have a frequency of 9999.6 kc., when a black area is being scanned, and when a white area is being scanned, the carrier may have a frequency of 10000.4 kc. It will be clear therefore, that with ordinary printed matter and the like the transmitted carrier will make a great number of excursions above and below its mean frequency during each complete transmission, the excursion in one direction from this mean frequency being equal to the excursion in the opposite direction.

At the receiving station, the shifted frequency carrier is applied to any well-known type of radio receiver, preferably of the beat frequency type, so as to produce beats representing the frequency excursions of the transmitted carrier. It will be understood of course, that the beat oscillator 10 at the receiver is designed to operate at a frequency which when beat against the signal from oscillator 7 will produce signal frequencies to operate the succeeding equipment.

The beats from receiver 9 which for example can be 2000 c. p. s., and 3000 c. p. s., are passed through a suitable input filter and limiter and then through a discriminator 11 whereby they are converted into corresponding pulsating D. C. signals. These signals are then applied to a low-pass filter 12 which suppresses the A. C. components and produces at its output variable amplitude D. C. signals corresponding to the original signals from cell 4. For a detailed description of a discriminator and filter arrangement that is suitable, reference may be had to U. S. Patent No. 2,299,937. As pointed out above, the signals applied to the discriminator 11 are substantially square-topped waves (Fig. 1A) rich in harmonics, but at the output of filter 12 they are substantially sinusoidal (Fig. 1B). In order to reconstitute the square-wave shape, the waves are applied to a peak limiting arrangement 13 or similar device which is so adjusted that for a small voltage above the base line B (Fig. 1B), the limiter is keyed "on," and at a small voltage below the line B, it is keyed "off"; thus producing the square wave of Fig. 1C. This square wave can then be used to control the recording element or printing hammer of any well-known form of telegraph reproducer or facsimile reproducer.

So long as the oscillators 7 and 10 do not drift in frequency, the half waves of the reconstituted keying signal (Fig. 1C) are symmetrical, both as to amplitude and time duration. I have found however, that if the frequency of the transmitter or receiver oscillator drifts, it will result in a shifting of the base line B (Fig. 1B), for example to the dotted line B'. The effect of this is that the limiter 13 will no longer operate symmetrically in the plus or minus directions, but rather will produce a wave form such as shown in Fig. 1D. In other words, in the example mentioned, the negative bias D will be much greater than the positive bias D'. This will result in improper operation of the recording element or keyer of the device 14.

In order to overcome these difficulties, there is interposed between the filter 12 and the limiter 13 a special network 15 (Fig. 2). The resistor 16 represents the load resistor in the output of the filter 12, the voltage across which is also changing between the two transmitted values corresponding to the signals from cell 4. On the positive swings of potential through resistor 16, condenser 17 is charged through rectifier 18 to the peak voltage of the signal. The time constant of resistor 16 and condenser 17 must be low enough so that condenser 17 will reach its full charge during the duration of the signal pulse. The voltage across resistor 19 during this positive excursion of the signal, remains zero. At the same time, because of the poling of rectifier 20, condenser 21 transmits the positive voltage across resistor 16 to resistor 22. When the voltage across resistor 16 restores to normal, the negative charge on condenser 17 is impressed across resistor 19. Thus, the voltage at point 23 swings equally on either side of zero with respect to ground at the values of the peak input signal voltages. When a negative voltage appears across resistor 16, the opposite effect occurs, so far as elements 17, 18, 19, and 21, 20, and 22, are concerned. Resistors 24, 25, are of equal value, therefore the voltage between 23 and ground will always vary equally in the plus and minus directions. The time constant of condenser 17 and resistor 19 must be such that the charge on condenser 17 will not leak off appreciably through resistor 19 between the extreme pulses, and likewise for condenser 21 and resistor 22. The point 23 is connected to the limiter 13 in such a way that for small changes of voltage in the positive direction, the limiter is keyed "on" and for small changes of voltage in the negative direction the limiter is keyed "off." When no voltage appears across resistor 16 or when the voltage across resistor 16 is constant, the voltage at point 23 with respect to ground is zero. The limiter 13 can then be adjusted so that this zero or quiescent condition holds the local circuit of the telegraph keyer 26 or recording element of the facsimile reproducer 14 in either "mark" or "space" position as desired. The mean or average voltage across resistor 16 will not disturb this balance, because no direct current is transmitted through condensers 17 or 21. Therefore, it does not matter whether the voltage across resistor B is varying about zero or about a plus or negative value. Only changes in voltages impressed across resistor 16 determine the extremes of the voltages at point 23. Thus, the transmitter or receiver can drift any amount, resulting in any mean voltage across resistor 16 without disturbing the balance. The circuit will operate equally well when only occasional pulses are being received rather than dots of equal on and off duration. In Morse signalling or teletype signals, the signals are far from symmetrical in regards to the on and off durations. An important application of this circuit is in teletype operation, where the slightest amount of "bias" (lengthening or shortening of the mark duration at the expense of the space) is extremely harmful.

As above pointed out, where the telefacsimile subject matter is "black" and "white," the transmitted carrier is statistically shifted between its extreme frequencies. However, if the subject matter 1 is a variable density or shade photograph, some means must be provided to shift the carrier between its extreme frequency excursions a multiplicity of times during the transmission. This can be effected by providing contrasting

"black" and "white" strips 24, 26, on the drum, thus a "black" and "white" strip may be interposed between the spaced edges of the picture 1 which is wrapped around the drum. Consequently, at each rotation of the drum, the carrier from the transmitter is shifted between its extreme frequency excursions. In the case of telegraph such as teletype or Morse signal transmission as above described, where only two extremes of signal conditions are encountered, the shifting of the carrier takes place automatically during transmission. In the case of a variable shade subject matter therefore, the point 23 instead of being connected through a limiter 13, may control the recording lamp 29 of any suitable telephoto recorder 23. Under these conditions, when point 30 is in its quiescent condition, sufficient current will flow through the recording lamp 29 to record mid-gray values of shade, whereas the two extremes in voltage appearing across resistor 16 will cause the voltage at point 23 to correspondingly vary between the blackest black and the whitest white. The half tones transmitted between these extreme tones will then always vary about the mid-gray value, and a transmitter or receiver frequency drift will not cause the average density of the photo-reproduction to vary. Various changes and modifications may be made in the disclosed embodiments without departing from the spirit and scope of the invention.

What is claimed is:

1. In an electric signalling system of the type employing a carrier whose frequency is purposely varied with respect to a mean frequency and between predetermined limits representing signals to be transmitted, means to receive said carrier and including a local oscillator to detect said signals, signal-reproducing means, circuit connections between said receiving means and said reproducing means and including a point whose potential corresponds to the said detected signals, and means between said receiving means and said point for varying the potential of said point only corresponding to said signals even though there exists undesired frequency drift in the said mean carrier frequency during said signal detection, the said means between said receiving means and said point comprising a capacity and rectifier network whereby the potential of said point changes only when the signal voltages impressed on said network are varying and independently of frequency drift in said local oscillator, said network including a pair of rectifiers having a common return and each connected through respective condensers to the said receiving means, a pair of rectifier load impedances having a common junction connected to said common return, and an output impedance bridged across both said rectifier load impedances, said point being located at the electrical midpoint of said output impedance.

2. In an electric signalling system of the kind employing a carrier whose frequency is shifted symmetrically in opposite directions with respect to a mean frequency under control of signals above and below a predetermined level, receiving means of the beat frequency detector type for detecting said signals, a filter for the detected signals for eliminating the frequency components outside a predetermined band, a network having an output point whose potential varies only when said detected signals vary, said network having a signal input point and including a pair of condensers and a pair of rectifiers oppositely poled

with respect to ground and connected across said condensers, means to impress the detected signals between said input point and ground, a load impedance connected across said rectifiers with the electrical midpoint connected to ground, another impedance connecting said output point symmetrically with respect to said first impedance, and a signal responder connected to said output point.

3. In a system of the character described, means to receive and detect signal voltages from a received frequency-shifted carrier, a signal reproducer, and a network between said receiving means and said responder for compensating for undesired frequency drift in the carrier, said network comprising a pair of conductors having their input ends bridged by a pair of condensers, and their output ends bridged by an output impedance, input impedance means to impress detected signals on the common junction point of said condensers, means connecting said signal responder to the electrical midpoint of said impedance, a pair of rectifiers bridged across said conductors adjacent said condensers, said rectifiers having a common return to said input impedance and being connected back-to-back with respect to said common return, a pair of impedances bridged across said conductors adjacent said first-mentioned impedances, said rectifiers and said pair of rectifier load impedances also being connected to said common return, and said rectifiers being oppositely poled with respect to said common return.

4. A receiving system for receiving a frequency shifted carrier whose frequency excursions are above and below a mean carrier base frequency, said receiver including in sequence a beat frequency detector employing a local oscillator, a frequency discriminator, a filter, a rectifier-capacitance network to compensate for undesirable frequency drift in the mean frequency of said carrier and to compensate for undesirable frequency drift in said local oscillator, a peak limiter which is keyed on and off in response to small changes in signal voltages from said filter, and a signal responder connected to said peak limiter, said network including a pair of rectifiers having a common return and each connected through respective condensers to said receiver, a load impedance for each rectifier, said load impedances having a common junction connected to said common return, and another impedance bridged across both said load impedances and to the electrical midpoint of which said signal responder is connected.

5. In a signalling system, means to scan a subject matter having "black" and "white" areas to produce symmetrical and substantially square-topped signal waves, a carrier generator, means to shift the frequency of said generator symmetrically around a mean frequency and between predetermined limits corresponding to said "black" and "white" areas, means to receive and detect said signals and including a frequency discriminator and filter for the detected signals, a frequency-drift compensating network having at least one input point and one output point, said network including a pair of rectifiers having a common return and connected back-to-back with respect to said common return, means connecting said rectifiers to the receiving means so that only the pulsating components of the detected signals are applied to said rectifiers, said

output being symmetrically connected to the combined output of said rectifiers so that said output point is maintained in a quiescent potential condition even though there exist undesired carrier frequency drifts in the system.

6. In a signalling system, electro-optical means to scan a picture or the like having a range of tone values between "black" and "white" to produce electric picture signals, means to shift the frequency of a carrier between predetermined limits corresponding to the extreme ranges of said tone values, means independent of the picture to subject the carrier to alternate frequency excursions between said predetermined limits, means to receive and detect the signals from said carrier, a picture shade reproducer, and means between the receiver and reproducer for reproducing a range of signal voltages corresponding to said picture signals with the mean value of the reproduced signals corresponding with the mean value of the original signals and independently of any accidental drift in the mean frequency of said carrier, said last-mentioned means including a pair of rectifiers having a common return and each connected through respective condensers to said receiver, a load impedance for each rectifier, said load impedances having a common junction connected to said common return, and another impedance bridged across both said load impedances and to the electrical midpoint of which said shade reproducer is connected.

7. A system according to claim 6 in which the means for subjecting the carrier to alternate frequency excursions independently of the picture comprises longitudinal "black" and "white" strips which are scanned in cyclical recurrent intervals between the ends of each scanning line of the picture.

8. In a system of the character described, carrier frequency drift compensating means comprising a pair of rectifiers connected in parallel with an impedance, a common ground return connection between the junction of the said rectifiers and the electrical midpoint of said impedance, said rectifiers being oppositely poled with respect to said common return, a pair of condensers connected in series across said rectifiers, a signal input impedance connected between the common junction of said condensers and said common return, whereby signal voltages are impressed in parallel on said condensers, a load impedance connected across said first impedance, a signal responder, and means connecting one terminal of said responder to the electrical midpoint of said load impedance and the other terminal of said responder to said common ground return.
